Makaniwa K. LUA,
INVENTOR

BY *Victor J. Evans*

ATTORNEY

UNITED STATES PATENT OFFICE

MAKAHIWA K. LUA, OF HONOLULU, TERRITORY OF HAWAII

PIN FASTENING

Application filed January 31, 1930. Serial No. 424,980.

This invention relates to certain new and useful improvements in safety or locking catches for jewelry, insignia and the like.

An object of the invention contemplates the provision and arrangement of a locking device of this character designed for engagement with the attaching portion of the form of jewelry or insignia.

An additional object of the invention consists in the arrangement of guide portions upon the attaching portions of the jewelry or insignia by means of which the locking element can be easily, effectively and expeditiously applied.

15 More specifically stated the locking element is provided with a flexible form of connection with the article of jewelry or insignia to prevent its being lost when not in use.

20 With the above and other objects in view, the invention further consists of the following novel features and details of construction, to be hereinafter more fully described, illustrated in the accompanying drawing and pointed out in the appended claims.

In the drawing:

Figure 1 is a fragmentary elevation of the conventional four-in-hand tie or cravat 30 showing a stick-pin applied in the knot thereof and exhibiting only that part of the stick-pin carrying the form of ornamentation.

Figure 2 is a side elevation of the present 35 invention with the locking element suspended therefrom.

Figure 3 is a sectional view taken on line 3-3 of Figure 2.

Figure 4 is a fragmentary longitudinal 40 sectional view taken through a portion of the attaching shank of the article of jewelry with the locking element applied.

Figure 5 is a horizontal sectional view 45 taken through the attaching shank with the locking element in use.

Figure 6 is a side elevation of the locking element per se.

Figures 7 and 8 are end elevations of the locking element.

50 Referring to the drawing in detail where-

in like characters of reference denote corresponding parts, the reference character 10 indicates generally the attaching shank of an article of jewelry, insignia and the like which is provided with a pointed or penetrating extremity 11 upon one end thereof. The shank being also bent upon itself or otherwise offset, as at 12, upon its uppermost end to facilitate the mounting and securing of a plate 13 having its exposed face covered or 60 treated with means of ornamental character.

55 The above construction is old and usual in stick or tie pin construction and forms no part of the present application for Letters Patent but is merely mentioned for purposes 65 of illustration in bringing forward the novel advantages of the present invention.

The invention primarily resides in the arrangement of an ear 14 carried by and depending from the offset or shoulder portion 70 12 upon the uppermost end of the shank 10 and immediately behind the plate 13. A chain or other flexible form of connection, such as indicated at 15, is joined at its uppermost end with the ear 14 incident to the passing of a 75 connecting link 16 through the aperture therein. The shank proper is provided with longitudinally extending cross sectional V-shaped grooves or recesses 17 upon diametrically opposite sides thereof and horizontally drilled at intervals thereon to provide passageways 18. These passageways are preferably located at the intersections of the oppositely and obliquely inclined side walls of the grooves or recesses 17, in the manner 80 suggested in Figure 5 of the drawing.

85 The locking element, alluded to in the foregoing, comprises a plate member 19 having a length of felt or packing, such as indicated at 20, upon the under face thereof designed for contacting engagement with the adjacent surface portion of the shank 10 right angularly disposed to each of the recesses 17 and in parallelism with the passageways 18. Spring 90 elements, such as indicated at 21, carried at intervals upon the under face of the plate member 19 and curved upon themselves in the manner shown in Figures 2, 5 and 6 of the drawing exert constant downward tension 95 with the penetrating elements 22 carried upon 100

the opposite ends thereof. These penetrating elements are designed for insertion within the passageways 18 and for subsequent locking engagement within the hooked extremities 23 of arms 24 disposed at intervals upon the opposite end of the plate member 19 and upon the under face thereof.

Although I have shown and described my invention as being designed for application upon the attaching shanks of stick or scarf pins, it is to be understood that I do not limit myself to this particular application inasmuch as the locking device may be equally and effectually as well applied upon the attaching shanks of badges, emblems, and other forms of insignia.

The invention is susceptible of various changes in its form, proportions and minor details of construction, and the right is herein reserved to make such changes as properly fall within the scope of the appended claims.

Having described the invention, what is claimed is:—

1. The combination of a pin having passageways in the attaching shank therefor, said shank being recessed longitudinally thereof and extending for appreciable distances beyond the passageways therein, said recesses being of V-shape in cross section, and of a locking element having arms guided terminally thereof upon the inclined side walls of the recesses toward the passageways for projection therethrough.

2. The combination of a pin having passageways in the attaching shank therefor, said shank being recessed longitudinally thereof and extending for appreciable distances beyond the passageways therein, said recesses being of V-shape in cross section, of a locking element having arms guided terminally thereof upon the inclined side walls of the recesses toward the passageways for projection therethrough, and retaining elements upon the locking element for the projecting extremities of said arms.

In testimony whereof I affix my signature.
MAKAHIWA K. LUA.
